COMBINED TRAY AND PIVOTAL ARM SUPPORT THEREFOR

Ronald C. Webb, York, Pa., assignor to Dentsply Research & Development Corporation, Wilmington, Del.

Filed Feb. 10, 1971, Ser. No. 114,407

Term of patent 14 years

Int. Cl. D6—06

U.S. Cl. D6—194

FIG. 1 is a side elevation of the tray arm of the present invention with the tray disposed nearer the viewer than the elbow of the arm.

FIG. 2 is a side elevation of the tray arm of the present invention with the elbow of the arm nearer to the viewer than the tray.

FIG. 3 is a side elevation of the tray arm of the present invention with the elbow folded so that the tray is near the tray arm support.

FIG. 4 is a plan perspective with the front edge of the tray nearest the viewer with the elbow bent at a right angle toward the viewer.

I claim:

The ornamental design for a combined tray and pivotal arm support therefor, substantially as shown.
